PETER JOHNSON, OF SAN FRANCISCO, CALIFORNIA, ASSIGNOR, BY DIRECT AND MESNE ASSIGNMENTS, OF ONE-THIRD TO OTTO SARI, ONE-THIRD TO GEORGE NEWMAN, AND ONE-THIRD TO ERVIN J. CASPER, OF SAN FRANCISCO, CALIFORNIA.

HASP-LOCK.

1,171,051.

Specification of Letters Patent.

Patented Feb. 8, 1916.

Application filed July 6, 1915. Serial No. 38,368.

To all whom it may concern:

Be it known that I, PETER JOHNSON, a citizen of the United States, residing at San Francisco, in the county of San Francisco, 5 State of California, have invented a new and useful Hasp-Lock, of which the following is a specification in such full and clear terms as will enable those skilled in the art to construct and use the same.

10 This invention relates to a hasp lock for doors, gates, etc., and its object is to produce a hasp lock which may be used either to lock the door or gate closed so that a key is required to open it, or to merely lock it 15 so that it can be opened conveniently by hand without the key if desired.

Other objects of the invention will appear as the description proceeds.

An embodiment of the invention is shown 20 in the drawing in which the same reference numeral is applied to the same portion throughout, but I am aware that there may be many modifications thereof.

Figure 1 is a sectional view through a 25 door and door post showing the hasp and lock in section as well, Fig. 2 is a side elevation of a door and post having this lock applied thereto, Fig. 3 is a plan view of the lock as it appears when the bolt is moved 30 part way in, but not completely locked, and Fig. 4 is a sectional view on a larger scale of a portion of the hasp adjacent the bolt and illustrating the stop for holding the lock bolt in an intermediate position.

35 The numeral 1 indicates the door, 2 the door post and 3 and 4 staples, one for connecting the hasp to the door and the other to the post. The hasp comprises a flat piece of metal 5 having an opening at 6 for the 40 staple 3, a slot at 7 for the staple 4 and a finger catch at 8 for operating the hasp. The hasp also has two loops of metal 9 and 10 formed therein which provide the slot for the bolt 11.

45 The bolt 11 has a notch 12 therein which is engaged by a depressed portion 13 of the loop 10 when the bolt is in an intermediate

position such as is indicated at 13 in Fig. 3, at which time the bolt may be retracted by simply pulling on the finger portion 14. 50 However, if the bolt is pushed through into the lock casing 15 a notch 16 near the end of the bolt will engage a tongue 17 on a spring 18, said spring being so placed with the lock casing 15 as to admit of its being 55 disengaged from the bolt 11 by passing the key through the hole 19 and turning the same slightly.

An advantage of the construction illustrated lies in the fact that it provides means 60 for locking the door or gate so that a key is required to open the same, or for locking it in such a manner as to allow it to be opened without the use of the key at will, all of the parts being very compactly assembled 65 upon the hasp plate 5.

Having thus described my invention what I claim as new and desire to secure by Letters Patent of the United States is as follows, modifications within the scope of the 70 claim being expressly reserved:

A hasp lock comprising a slotted plate having an opening at one end, a bolt 75 slideable on the plate over the slot and carried by guides thereon, means to prevent the bolt from being removed from the plate, a notch on the bolt for holding said bolt partially extended, means on one of the bolt guides for coöoperating with said notch when the bolt is in said partially extended position 80 to allow the bolt to be removed from the staple passing through the slot in the plate without the use of the lock, and a lock casing into which said bolt passes after passing over the slot for preventing the withdrawal of the bolt without the use of a key. 85

In testimony whereof I have hereunto set my hand this 21st day of June, A. D. 1915, in the presence of the two subscribed witnesses.

PETER JOHNSON.

Witnesses:

OTTO SARI,
CARLOS P. GRIFFIN.
